(57) CLAIM

I claim the ornamental design for a precut tape with surface ornamentation, as shown and described.

DESCRIPTION

FIG. 1 is a front view of a precut tape with surface ornamentation showing my new design;

FIG. 2 is a side view thereof;

FIG. 3 is a rear view thereof;

FIG. 4 is a bottom view thereof; and,

FIG. 5 is a top view thereof.

The broken lines in the drawings depict the boundaries of the claim and form no part thereof.
